INVENTOR
JOHN ELDER.

BY Felicia Dorothea Robins.

UNITED STATES PATENT OFFICE.

JOHN ELDER, OF RAYMOND, ALBERTA, CANADA.

WIRE STRETCHER AND SPLICER.

Application filed January 27, 1922. Serial No. 532,302.

To all whom it may concern:

Be it known that I, JOHN ELDER, a subject of the King of Great Britain, and resident of Raymond, in the Province of Alberta and 5 Dominion of Canada, have invented certain new and useful Improvements in Wire Stretchers and Splicers, of which the following is a specification.

This invention relates to improvements in 10 wire stretchers and splicers, and the objects of the invention are to provide a practical and economically constructed device of this character that will efficiently stretch fence wire or the like in a convenient and readily 15 operated manner.

A further object is to provide in the present device a super-stretcher and splicer with which it is possible to strain wires, clamp them when strained, and then give them a 20 second or additional super-strain without losing any of the slack from the first strain.

With these and other objects hereinafter more fully described in view, the invention consists essentially in the combination with 25 a Y-shaped member provided with eccentric clamping means, of an operating third arm pivotally mounted on the Y-member and provided with similarly constructed clamping means, and designed to further stretch the 30 wire already stretched by the Y-member.

Referring to the drawings, in which like characters of reference indicate corresponding parts in each figure, and in which:

Figure 1 is a plan view, showing two wires 35 clamped by the Y-member.

Figure 2 is a similar view, showing the two wires still clamped by the Y-member and one of them also clamped by the auxiliary member.

Figure 3 is a similar view, showing one 40 wire still clamped by the Y-member and the other wire clamped only by the auxiliary member.

Figure 4 is a similar view, showing one 45 wire still clamped by the Y-member and the other wire clamped by the auxiliary member and the Y-member.

Figure 5 is a detail of the eccentric clamp.

Figure 6 is a sectional detail through 50 Figure 5.

In the drawings:

A is the combined wire puller and stretcher preferably formed (as here shown) of metal, and comprising a single Y-shaped member 10 having integral arms 11 and a handle portion in common 12. At the ex-

tremities of the arms 11 are fixedly secured to the blocks 13.

15 are clamping members designed to engage with the blocks 13 to clamp the wire 60 therebetween and comprise a toothed and recessed eccentric 16 pivotally mounted in operative relationship to the blocks 13 and provided with a handle piece or plate 17 fixedly secured thereon at 18.

In addition to the Y-member 10 and arms thereon, I provide an auxiliary or third arm 19 pivotally mounted at 20 on one of the arms 11. This arm or operating member 19 is substantially of semi-circular formation and provided at its outer extremity with similarly constructed clamping means to those already described as being provided on the arms 11.

In the form of my invention here shown, 75 it will be noted that the eccentric 16 is placed below the block 13 instead of above it on the right arm of the Y-shaped member 10 so that it will not contact with the swing of the operating arm 19.

21 is the forked end of the handle designed to draw staples and the like. 22 and 23 represent the wires to be drawn.

In operation, to tighten the loose fence wires to repair breaks rapidly and perfectly, 85 first splice a short piece of mending wire to one end of the broken wire sufficient to allow the wires to overlap about a foot or two when drawn together by hand. (The splicing is made by inserting a spike or other 90 suitable instrument not shown between the two taut wires midway between the Y-arm and turn this instrument around a few times, the wires at the same time being both clamped in the Y-arms).

The wire 22 is then clamped on the right Y-arm and the wire 23 is then carried thereunder and clamped on the left Y-arm, as in Figure 1. The movable arm 19 is then swung around on top of the wire 22, and 100 the wires are given the first stretch, bringing the wire puller from an oblique position to a vertical position. It should here be noted that, in making the first stretch on loose wires, the arm 19 is only used to swing 105 over not to clamp wire 22, in order to keep the stretcher from flipping or flopping over if the pull is hard.

When the first pull is made, swing the arm 19 backward or downwards and clamp 110 it on wire 22, as in Figure 2. Things are then ready for the second pull. Now release

- wire 22 from right Y-arm clamp, as in Figure 3, and move the stretcher handle until the stretcher is in an oblique position, as shown in Figure 4, then fasten wire 22 again 5 in the right Y-arm clamp and release it from the arm 19, swing the latter over wire 22 and make the second pull. The wire is now as tight as will probably be required, but, if not, repeat the operation.
- 10 In pulling up and stretching new fence wires, the wire is clamped on one of the Y-arms, the other Y-arm embracing one of the fence posts. The handle is then pulled or drawn until the said other arm meets the 15 wire around the post, when staples or other securing means are used to secure the stretched wire on the post. If required and has been found in some cases more satisfactory, the construction of my stretcher may 20 be altered with advantage by changing the member 17 on the eccentric clamp 19 and mounting it instead on the solid block 13. This alternative construction prevents the wire from jumping out.
- 25 As many changes could be made in the above construction and many apparently widely different embodiments of my invention within the scope of the claims, constructed without departing from the spirit 30 or scope thereof, it is intended that all matter contained in the accompanying specification and drawings shall be interpreted as illustrative and not in a limiting sense.

What I claim as my invention is:

1. A wire stretcher and splicer comprising 35 a Y-shaped member, the arms of which are inwardly curved and provided with clamping means thereon, an operating arm pivotally mounted on one of the Y-arms and provided at its outer extremity with clamping 40 means similarly constructed to that on the Y-arms whereby, in combination with said Y-arms, further straining means are provided for a wire or wires.

2. A device of the character described 45 comprising a pair of fixed arms having a handle in common, a pivotally mounted third arm, eccentric clamping means on said arms comprising a block and a pivotally mounted eccentric formed with a handle and 50 corrugated on the inside thereof to engage with said block in gripping a wire there-between.

3. A triple-armed wire puller and splicer 55 having eccentric wire clamping means there-on, two of said arms being fixed and operated by a common handle, the third of said arms being operatively mounted and de-signed to swing around the two arms.

In witness whereof I have hereunto set 60 my hand in the presence of two witnesses.

JOHN ELDER.

Witnesses:

ARTHUR MULHOLLAND DOWSLEY,
ALFRED WALKER KRESS.
